UNITED STATES PATENT OFFICE.

WILLIAM HAMILTON, OF DAYTON, OHIO.

ELEVATOR.

SPECIFICATION forming part of Letters Patent No. 743,717, dated November 10, 1903.

Application filed July 20, 1903. Serial No. 166,238. (No model.)

To all whom it may concern:

Be it known that I, WILLIAM HAMILTON, a citizen of the United States, residing at Dayton, in the county of Montgomery and State of Ohio, have invented certain new and useful Improvements in Elevators; and I do declare the following to be a full, clear, and exact description of the invention, such as will enable others skilled in the art to which it appertains to make and use the same, reference being had to the accompanying drawings, and to the figures of reference marked thereon, which form a part of this specification.

15. This invention relates to improvements in elevators.

The object of the invention is to provide means operated by the moving car of the elevator to close each entrance without the use 20 of doors.

Preceding a detail description of my invention, reference is made to the accompanying drawings, of which—

Figure 1 is a vertical front elevation of a portion of an elevator-shaft, showing my improved elevator mechanism in position therein. Fig. 2 is a vertical side elevation. Fig. 3 is a side elevation of the upper portion of the elevator-shaft, showing the mounting of the upper drum. Fig. 4 is a similar view showing a modification in the mounting of the upper drum in cases where the space in the upper portion of the elevator-shaft is limited. Fig. 5 is a detail view of a portion of the safety-belt, showing a modification in the construction thereof. Fig. 6 is a sectional view of a portion of the elevator-car adjacent to the roof. Fig. 7 is a horizontal section on the line *a-a* of Fig. 6.

40. Throughout a detail description of the invention similar reference characters indicate corresponding parts.

1 designates the rear and side walls of an elevator-shaft. This elevator-shaft has in the 45 front thereof the usual openings 2, which in the present instance are not provided with the usual doors. Within said shaft is placed a car 3, which is elevated and lowered by any suitable power through means of the usual 50 cable 4, passing over the usual pulley 5. Connected to the floor 6 of the elevator-car at 7 is one end of a safety-belt, which may be con-

structed in a variety of forms—such, for example, as that shown in Fig. 5 or as that shown in Figs. 1 and 2, which consists of two 55 belts 8, which are joined by a plurality of cross-pieces 9, which form barriers on the interior of the openings 2 as the elevator descends. As before stated, the ends of the belts 8 are attached at 7 to the floor of the 60 elevator-car, and from that point they pass downwardly around rollers 10, which are mounted in the lower extremity of the elevator-shaft. The said safety-belt passes upwardly in the rear portion of the elevator-shaft around a drum 11, which is mounted in the upper portion of the elevator-shaft above 65 the beam 12, on which the pulley 5 is mounted. The shaft 13 of said drum is mounted in journal-boxes 14, which are supported at each 70 end of the shaft by means of elliptical springs 15, or said springs may be of any suitable character, their function being to provide a yielding support for the drum in the event that the elevator-car should break from its 75 cable support. The strength of the springs 15 is sufficient to hold the drum 11 up in its normal position, as in Fig. 2. The safety-belt is held taut in this manner. The spring 15 is supported below by a clip 16 and above 80 by a similar clip 16, which is attached to the lower member of the box-bearing 14. The clips 16 and the boxes 14 are inclosed and guided between two side brackets 17, which have their ends rigidly united to the beams 85 of the elevator-shaft.

19 designates a series of pins around the periphery of the drum 11, which move between the spaces in the belt and prevent said belt from slipping or moving out of the proper 90 position during the movements of the elevator.

18 designates a series of horizontal bars secured between the side walls of the shaft and across said shaft immediately below the drum. 95

20 designates a spider, of which there is one rigidly secured to each end of the drum 11. These spiders in the normal movements of the drum move above the bars 18; but in the event of the drum dropping through any accidental breaking of the elevator-cable 4 the arms of said spider become interlocked with the bars 18, and said drum is thus prevented from rotation when in such position.

As before stated, one end of the safety-belt is attached to the bottom of the elevator, and I will now proceed to describe the manner of attaching the other end of said belt.

Referring to Figs. 6 and 7, the belt is secured at the top and in the front of the elevator-car to rollers 21, which are mounted on a shaft 22, having its ends journaled in suitable bearings. 23 designates two arms which are rigidly united to the rollers 21, and consequently are subjected to any movements that the rollers 21 may receive from the safety-belt 8. The upper ends of said arms 23 are pivotally connected at 26 to horizontal bolts 24, which lie at right angles to the shaft 22 and project through openings 25 in the rear wall of the elevator-car. In the event of the cable of the elevator-car snapping or in the event of any other accident happening which might release the elevator-car it will be readily seen from Fig. 2 that the weight of said elevator-car will be transferred wholly to the safety-belt 8 and thence to the drum 11. This will cause said drum to contract the springs 15, upon which its journals are supported, until the arms of the spider 20 engage with the cross-bars 18, at which time any rotary movement of said drum will cease. Simultaneously with the dropping of the drum 30 the tension upon said safety-belt 8, due to the weight of said elevator-car, will cause the rollers 21 to turn upon the shaft 22 a sufficient extent to throw the bolts 24 outwardly to enter the spaces between any of the cross-bars 9 of said safety-belt and between rods 27, which are arranged in the back of the elevator-shaft throughout the length of said shaft. It will therefore be seen that the said locking-bolts 24, so operating to engage the safety-belt and the horizontal bars 27, will securely maintain the elevator in a stationary position. The elevator-car is instantly stopped as soon as the locking-bolts 24 are thrown rearwardly and the drum 11 is securely held from turning by the spider-arms engaging with the cross-bars 18, as before stated, and thus the elevator is caught and prevented from falling through the shaft.

Referring now to Fig. 4, the construction shown therein is designed for elevator-shafts with limited space above in which the drum 11 is to be mounted—such, for example, as where the roof of a building encroaches upon the space necessary for the drum. In this case the drum is mounted between two other drums 30 and 31 upon a frame or carriage 32, which incloses the outer sides of the elevator-shaft and rests upon a suitable number of coil expansion-springs 28, which hold said frame, with the drums, in an upper or normal position. The coil-springs 28 are inclosed at their upper ends by flanges 33, which project laterally from suitable points of the frame or carriage, and the lower ends of said springs are similarly confined by flanges 34, which project laterally from the exterior surface of the elevator-shaft. The two outer drums 30

and 31 are instrumental in spreading the safety-belt 8, this being necessary in view of the fact that there is not suitable space above 70 for mounting the drum 11. The safety-belt at the front of the elevator is inclosed between outer and inner walls 36 and 37, so that in looking at the front of the elevator, as shown in Fig. 1, there will be no part of the belt visible, excepting the barriers 9, which will be seen extending across each opening as the elevator descends from the last opening at which it has been stopped, and when the elevator has reached the extreme lower limit of its movement all of the doors or openings throughout the length of the shaft will be closed by these barriers. 75 80

While I have shown different constructions of safety-belts and have also shown and referred to different ways of mounting the safety-belt drum, I do not wish to limit myself to any specific way of constructing the safety-belt and in mounting the drum. 85

Having described my invention, I claim— 90

1. In an elevator, the combination with an elevator-shaft having the usual openings, and an elevator-car within said shaft, of a safety-belt having its ends secured to said elevator-car, rollers located in the bottom of the elevator-shaft and around which said safety-belt passes, a drum located in the top of said elevator-shaft and around which said safety-belt passes, and yielding bearings upon which said drum is mounted, substantially as set 95 forth. 100

2. In an elevator, the combination with an elevator-shaft, a car within said shaft, a flexible safety device having its ends secured to opposite points of the elevator-car, rollers located in the bottom of the elevator-shaft and around which said safety device passes, a drum located in the top of said elevator-shaft and around which said safety device passes, yielding supports for said drum, and means for interlocking the drum when moved out of its normal position to a lower position in the elevator-shaft, substantially as set forth. 110

3. In an elevator, the combination with an elevator-shaft having the usual openings 115 therein, and a car within said elevator-shaft, of a safety-belt having its ends secured to opposite points of said elevator-car, rollers located in the bottom of the elevator-shaft and around which said safety-belt passes in the rear of the elevator-shaft, a drum mounted on bearings in the upper part of the elevator-shaft, said bearings being of a yielding nature, radial arms projecting from the ends of said drum, and a series of horizontal rods 120 mounted in the elevator-shaft adjacent to the lower side of the drum, said radial arms and horizontal rods being adapted to interlock when the drum is drawn to a lower position from its normal position, and devices adapted 125 to be actuated by undue tension on the safety-belt and whereby said safety-belt is locked against movement, substantially as set forth. 130

4. In an elevator, the combination with an elevator-shaft, and an elevator-car therein, of a safety-belt having opposite ends attached to said elevator-car, said safety-belt being adapted to form a barrier to the entrances of the elevator-shaft as the car moves downwardly, rollers at the bottom of the shaft around which said safety-belt passes, a drum located in the upper portion of the shaft and around which said belt passes, safety devices adapted to support said drum in the event that it is called upon to support the weight of the elevator, and safety devices actuated by tension on the safety-belt due to the weight of the elevator-car being transferred to said safety-belt through any accidental releasing of the elevator-car from its normal support, and whereby the safety-belt is utilized to support the elevator, substantially as set forth.
5. In an elevator, the combination with an elevator-shaft, and an elevator-car, of a safety-belt comprising a plurality of parallel cross-bars which are adapted to form barriers to the

entrances in the elevator-shaft, said safety-belt having its opposite ends attached to the elevator-car, rollers located at the bottom of the elevator-shaft, and a drum located at the top of the elevator-shaft around which the safety-belt passes, means on said drum for guiding and maintaining the safety-belt in position, devices for supporting and arresting the movement of the drum in the event of the removal of said drum from its normal position, and levers and rods actuated by said safety-belt when undue tension is applied to said safety-belt and whereby the movement of the elevator-car is released in the event of any accidental breaking of the operating devices of the elevator, substantially as set forth.

In testimony whereof I affix my signature in presence of two witnesses.

WILLIAM HAMILTON.
